UNITED STATES PATENT OFFICE.

JAMES F. FERRY, OF LEADVILLE, COLORADO.

LIQUOR-TAPPING MEANS.

936,877.

Specification of Letters Patent. Patented Oct. 12, 1909.

Application filed July 3, 1908. Serial No. 441,722.

To all whom it may concern:

Be it known that I, JAMES F. FERRY, residing at Leadville, in the county of Lake and State of Colorado, have invented a new 5 and Improved Liquor-Tapping Means, of which the following is a specification.

This invention which relates generally to improvements in devices or means for withdrawing liquor from a barrel or other receptacle, more particularly has for its object to provide an improved construction of faucet or beer taps, that can be conveniently applied for use, is not likely to become deranged or injured in ordinary usage, by 10 means of which the liquor can be effectively drawn when the receptacle is in either a vertical or horizontal position and a clear flow of the liquor maintained as desired.

My invention also has for its object to 20 provide a tap or faucet of the general character stated, in which is included a closure member combined with the tap shell or casing in such manner that dirt and other extraneous substances are prevented from collecting in the tap, and which obviates the 25 undue loss or escape of the liquor.

Another and essential object of my invention is to provide an improved device of the general character stated that can be readily 30 adapted for use as an air vent or tap for controlling a fluid pressure inflow to the keg or other liquor holding receptacle.

The invention consists in the peculiar combination and novel arrangement of the parts 35 hereinafter described in detail, specifically pointed out in the appended claims and illustrated in the accompanying drawings, in which:—

Figure 1, is a longitudinal section of the 40 preferred form of my invention, the parts being positioned for a free outflow of the liquor. Fig. 2, is a horizontal section thereof taken on the line 2—2 on Fig. 1. Fig. 3, is a similar view on the line 3—3 on Fig. 1. Fig. 4, is a view similar to Fig. 3 with the 45 closure member positioned to close the tap. Fig. 5, is a vertical section of a modified form of my invention hereinafter referred to. Fig. 6, shows my form of faucet or tap 50 with a "goose neck" connection hereinafter explained.

In the practical construction, my invention embodies a main or bushing member B

externally threaded as at *b* for securing it in the cask or barrel, its inner end being of 55 a reduced diameter as at *b'*, also externally threaded to form a seat for the threaded flange *a* of the cap plate A that has the nut portion *a'* for receiving a wrench and that also has elongated openings *d* for the escape 60 of the liquor from the holding vessel. The inner end of the bushing B is formed with an internal beveled valve seat *b*² for receiving the beveled rim *c* of a hollow valve C, that has a tubular shank *c'* that snugly fits 65 but freely turns in the bore of the bushing as clearly shown in the drawings.

In assembling the parts, the hollow valve C is first inserted into the inner end of the bushing B, after which the cap A is screwed 70 on the bushing and brought up tight so as to make a close fitting of the valve C against the cap A and its beveled bearing rim against the valve seat that it engages, and for providing a tight closure of the said 75 engaging parts, the beveled bearing and the inner bearing portions of the valve, the bushing and the cap are finished up to form ground joints. The inner or cap end of the valve C is also formed with elongated liquor 80 passages *c*² that register with the openings *d* in the cap A under one adjustment of the valve C and are cut off therefrom under another adjustment of the valve. Valve C has two or more elongated recesses *c*³—*c*³ on the 85 internal face and at the outer end for receiving radially projected lugs *g*—*g* on the inner end of a tubular faucet key G, which key is also formed with shoulders *g*'—*g*' for engaging a washer F formed of leather or 90 other yieldable material that seats on the outer end of the valve C. The outer end of the bushing B is also formed with two or more radial notches *b*⁵ that merge with the oppositely directed under cut grooves *b*⁶ 95 for receiving the lugs *g*⁶ on the member G and that slip down into the notches *b*⁵ when the parts are assembled.

By reason of constructing the several parts in the manner shown and described, when 100 the faucet key G is turned in one direction, that is, one-quarter of a revolution, the lugs *g*⁶ in engaging the grooves *b*⁶, which, being slightly inclined, causes the shoulder *g*' to bear against and tighten the washer F and 105 at the same time causes a tight bearing of

the inner end of the valve C against the cap A as the apertures C are cut off from the outlet apertures α in the cap. To turn on the flow, it is only necessary to give the 5 faucet G a one-fourth turn in the other direction to bring the liquor passages into register.

It should be here stated that the radial slots or recesses into which the lugs g are 10 slipped, are so disposed, relatively to the set of the valve C, that the said lugs interlock with the grooves b^3 when the tap is open and liquor flowing and hence the said faucet G cannot be withdrawn when drawing 15 liquor. It can, however, be readily removed when the flow of liquor is shut off.

In Fig. 5, I have shown a modified form 20 of my invention, in which the parts are especially designed for use in admitting air into the cask or barrel on top of the liquor to create the desired flow when the spigot is turned on. In this form the bushing B, the cap A, the faucet or valve C are combined the same as in the form shown in Fig. 1 but 25 the faucet key has a special construction and combines with other parts that control the atmospheric pressure through the tap when the valve C is turned on. In this latter form, the tubular key G has a threaded socket c^5 30 into which screws the nozzle plug 4, that has a wrench or nut portion 40 and which receives the hose 41 open to atmosphere or a pressure tank. A metal bushing 2, whose flange 20 rests on a thin leather washer 3 is 35 clamped in place by the nozzle 4 and it carries a rubber air valve, 1.

In the use of the construction last described, when the faucet G is turned on to 40 bring the apertures in the valve C and the cap plate in register, the air passes through the valve 1 into the cask on top of the liquor, it being obvious that turning off the valve C cuts off the air pressure. Since some liquors have sediment and other gritty substances, a 45 gauze covering α may be used on the inner end of the faucet G and held thereon in any approved manner. For clear liquors the member α is not necessary.

In Fig. 6, I have illustrated my improved 50 faucet or tap as combined with a goose neck connection and in this form the goose neck 30 connects with the faucet neck 31 by a union coupling, the meeting ends of the members 30 and 31 having beveled ground 55 joint faces 51—52, the faucet neck 31 having external threads 32 and the goose neck 30 having a shoulder 33 to receive the flange 34 of the coupling 35 that screws onto the threads 32. 36—36 are set screws to keep 60 the coupling on the goose neck. By making a goose neck connection as described, it can be turned around without moving the key member G of the faucet and for drawing liquor into the barrel when horizontal or

when on end, and it can be used so that a 65 thin pipe or hose can be readily attached.

Having thus described my invention, what I claim is:

1. The combination with a bushing having 70 passages through its inner end, parallel with the bore of the bushing, a hollow rotary valve mounted within the bushing and having an end wall provided with passages to coöperate with those of the bushing, a key projecting into the bushing and into the valve, an 75 air check valve carried by the key to permit air to pass through the key and valve in one direction only.

2. The combination with a bushing having 80 passages through its inner end, parallel with the bore of the bushing, a hollow rotary valve mounted within the bushing and having an end wall provided with passages to coöperate with those of the bushing, a key projecting into the bushing and into the valve, an 85 air check valve carried by the key to permit air to pass through the key and valve in one direction only, and means for causing the key to interlock with the hollow valve and with the bushing. 90

3. The combination with an externally threaded bushing having an internal annular bearing portion terminating in a conical portion at one end, a cap removably held over 100 said end and provided with fluid passages, a valve rotatably mounted within the bushing to engage said bearing portion, said valve having a conical portion to engage the conical portion of the bushing, said valve having a bore entering from one end and terminating short of the other end to provide a diaphragm to engage said cap and having apertures in said diaphragm, which when the valve is in one position registers with the 105 apertures of the cap, said valve having slots and said bushing having bayonet slots, a key member insertible into said bushing and into said valve, said key member having lugs to enter the slots of the valve and other lugs to enter the bayonet slots of the bushing, a 110 packing ring interposed between the open end of the valve and the key member, substantially as shown and described. 100

4. The combination with an externally threaded bushing having an internal annular bearing portion terminating in a conical portion at one end, a cap removably held over 115 said end and provided with fluid passages, a valve rotatably mounted within the bushing to engage said bearing portion, said valve having a conical portion to engage the conical portion of the bushing, said valve having a bore entering from one end and terminating short of the other end to provide a diaphragm to engage said cap, and having apertures in said diaphragm, which when the valve is in one position register with the 120 apertures of the cap, said valve having slots 125

and said bushing having bayonet slots, a key member insertible into said bushing and into said valve, said key member having lugs to enter the slots of the valve and other lugs to enter the bayonet slots of the bushing, a nozzle plug insertible into said key member and secured thereto, a one-way valve carried by said nozzle plug and projected into said

tubular valve to permit passage of air through the tubular valve in one direction only.
